UNITED STATES PATENT OFFICE.

MURRAY G. DOUGLASS, OF LEOMINSTER, MASSACHUSETTS, ASSIGNOR TO TENNEY & PORTER, INC., OF LEOMINSTER, MASSACHUSETTS, A CORPORATION OF MASSACHUSETTS.

DESIGN FOR A SHOEHORN.

Application filed February 3, 1927. Serial No. 20,599. Term of patent 3½ years.

To all whom it may concern:

Be it known that I, MURRAY G. DOUGLASS, a citizen of the United States, residing at Leominster, in the county of Worcester and State of Massachusetts, have invented a new, original, and ornamental Design for a Shoehorn, of which the following is a specification, reference being had to the accompanying drawing, forming part thereof.

Fig. 1 is a plan view of a shoe horn, and Fig. 2 is a side elevation of the shoe horn shown in Fig. 1, both figures showing my new design.

I claim:

The ornamental design for a shoehorn as shown.

MURRAY G. DOUGLASS.
